UNITED STATES PATENT OFFICE

162,059

BUTTER SPREADER OR SIMILAR ARTICLE

Wolford A. Morris, Springfield, Ill., assignor to Restaurant Products, Springfield, Ill., a firm

Application November 3, 1950, Serial No. 12,831

Term of patent 14 years

(Cl. D44—29)

To all whom it may concern:

Be it known that I, Wolford A. Morris, a citizen of the United States, residing at Springfield, county of Sangamon and State of Illinois, have invented a new, original, and ornamental Design for Butter Spreader or Similar Article, of which the following is a specification, reference being had to the accompanying drawing, forming part thereof.

Figure 1 is a top plan view of the butter spreader or similar article embodying my new design;

I claim:

The ornamental design for a butter spreader or similar article, substantially as shown.
WOLFORD A. MORRIS.
